ELECTROMAGNETIC SWITCH

Edward John Diebold, Ardmore, Pa., assignor to I-T-E Circuit Breaker Company, Philadelphia, Pa., a corporation of Pennsylvania

Application November 23, 1951, Serial No. 257,901

27 Claims. (Cl. 321—48)

My present invention relates to electromagnetic switches and more particularly to an electromagnetic switch having an auxiliary winding in combination with a commutating reactor.

Heretofore in the prior art various devices were used to provide a uni-directional current from an alternating current. Each of these devices inherently have disadvantages which the present invention proposes to alleviate.

Dry cell rectifiers or selenium rectifiers have the disadvantage of ohmic losses in the forward direction and relatively low reverse resistance so that there are considerable losses as current flows in the reverse direction. Gas discharge tube rectifiers and mercury arc rectifiers present a substantial arc voltage drop. Moreover, the gas discharge tube and mercury arc rectifiers require an interval of time to heat up and are additionally sensitive to changes in temperature. A motor generator set used as a rectifier has the disadvantage of large initial cost, large bulk and has losses due to the transformation from electrical energy to mechanical energy and back again to electrical energy.

Mechanical rectifiers occupy a small volume and have high efficiency but they require a synchronous motor drive which makes them subject to backfire whenever the load, the voltage or the frequency exceed a relatively narrow limit.

The present invention overcomes the limitations of the prior art by providing an electromagnetic switch having a magnetization coil and a commutating reactor in series with the contacts. The commutating reactor essentially restrains the current through the switch to a relatively low value when the switch opens or closes.

It is then an important object of the present invention to provide an electromagnetic switch or valve which has a resistance when conducting in the order of milliohms or less.

The utilization of electromagnetic switches having in the associated circuitry saturable transformers and reactors materially increases the cost of such a switch.

If the transformer is to be easily saturable and have an air gap, almost unsurmountable manufacturing difficulties arise, as the desirable characteristics are lost when an air gap is cut into such a core or when the core is made in two valves and assembled.

Moreover, electromagnetic switches as utilized in the prior art require heavy expensive windings.

Another important object of the present invention is then the provision of a novel electromagnetic switch having a minimum of associated coil and winding.

Another important object of the present invention is the provision of a novel electromagnetic switch having a low recovery volt across its opening contacts.

Another important object of the present invention is the provision of a novel electromagnetic switch having relatively few heavy windings.

Another important object of the present invention is the provision of a self-operating rectifier that is instantaneously ready for operation, independent of the ambient

2

temperature and having a high efficiency and small volume.

Another important object of the present invention is the provision of a novel electromagnetic valve where the inrush and break currents through the valve contacts are always maintained at a low value independent of the voltage load, number of phases or frequencies.

Another important object of the present invention is the provision of a novel rectifier having a control by means of a current which is much smaller than the output of the rectifier.

Another object of the present invention is the provision of a novel saturable transformer without an air gap having the characteristics of a transformer having an air gap.

Another important object of the present invention is the provision of a rectifier where the transition from one mode of commutation to another occurs without disturbance.

Further objects and advantages will become apparent on consideration of the following description in connection with the drawings in which

Figure 19 is a modification of the electromagnetic switch of the present invention.

Referring now to Figure 1 the novel electromagnetic valve circuitry of the present invention is connected between the points 21 and 22. The source of alternating voltage 23 provides the power to the load 24 which is connected in series with the electromagnetic valve circuitry connected between 21 and 22 and the source 23. The load 24 may be inductive, capacitive or resistive, or any combination thereof.

The electromagnetic switch or valve 25 has two iron cores 26 and 27 which are connected electrically, as

hereinafter described, to the two terminals of the switch 25. The magnetic poles 26 and 27 are connected by a small bridge contact 28 which makes an electrical and a magnetic connection therebetween. In order to achieve a good electric and magnetic connection the movable bridge or armature 28 is made of a magnetically soft material, as iron, and coated with a layer of high conducting material, as silver or gold. The stationary poles 26 and 27, as shown in Figures 2 and 3 are surrounded by copper conductor 29 and 30 which serve the double purpose of carrying the current and conducting the heat generated in the small armature 28 away from its source. For high current carrying capacity the conductors 29 and 30 may be equipped with cooling fins, now shown.

Referring again to Figure 1, the electromagnetic switch 25 has a main winding 31 connected in series with the switch poles 26 and 27 and the armature 28. The winding 31 essentially magnetizes the magnetic poles 26 and 27 when a current flows therethrough. The current flowing through the coil 31 causes the armature 28 to be attracted and held tightly against the magnetic poles 26 and 27.

As shown in Figures 2 and 3, the current from the copper conductor 29 is carried to the armature 28 across a small steel silver plated plate 32 which lies across the pole face of the magnetic pole 26. An identical plate 33 carries the current to the conductor 30 across the pole face of the magnet 21. The plates 32 and 33 are each held in position by two screws 38. The armature 28 is suspended by spring 34 held between a clamped plate 35 and two insulators 36. The spring 34 resiliently restrains the armature 28 against the bumper 37 which is essentially a stack of thin laminations. The laminations absorb the shock of the armature 28 preventing rebound.

Referring again to Figure 1, the electromagnetic switch 25 carries a premagnetization winding, polarization winding, or auxiliary winding 40 on the pole 26. The winding 40 carries a direct current supplied by a battery 41 which also provides through a coil 42 the preexcitation for the core 43 of the commutating reactor 44. The commutating reactor has its main coil 45 connected in series with the switch 25 and also with a winding 46 of the transformer 47. Connected then between the points 1 and 2 in series is the winding 46, the winding 45, the pole 26, the armature 28, the pole 27 and the coil 31, all described above. The transformer 47 consists of a core 50 having an air gap 51 upon which are wound the three coils 46, 52 and 53. The coil 53 is connected through an impedance 58 across the alternating voltage source 23. The coil 52 is connected on one side to the junction between the coils 46 and 45 and on the other side through a selenium rectifier 55.

The rise of current through the switch 25 is initiated through the selenium rectifier 55 and kept away from the armature 28 for the time interval necessary to close the switch plus an additional interval necessary to increase the current through the main winding 31 to a relatively high value sufficient to assure a good contact, as is hereinafter described in reference to the curves shown in Figure 4.

The curves drawn in Figure 4 have the same time axis and are hereinafter described before proceeding with the analysis of what occurs during the make or break intervals of the cycle during the times t_0 to t_8 .

Figure 4a shows the distribution of the voltage on the electromagnetic switch 25, indicated as e_{25} , and on the load 24, indicated as e_{24} . The curve of e_{24} shows that the voltage across the load is mainly positive and the curve of e_{25} shows that this voltage is mainly negative. Except for a short interval between the times t_1 and t_2 at the beginning of the positive half cycle and between the times t_5 and t_8 at the beginning of the

negative half cycle, the two voltages e_{24} and e_{25} in the positive and negative portion thereof are respectively equal to the generator voltage e_{23} , which is shown as a thin solid line in Figure 4b.

Figure 4d shows the current i_{24} through the load 24, through the alternating voltage source 23 and through the coil 31. The current i_{24} is shown lagging the voltage e_{24} as the load 24 is considered for the present discussion to be resistive and inductive.

Figure 4b in addition to showing the voltage e_{23} also shows the voltage across the winding 46 of the saturable transformer 47 as a heavy solid line.

Figure 4c shows the voltage across the winding 45 of the commutating reactor 44, and

Figure 4e shows the current i_{55} through the selenium rectifier 55.

Figure 4f shows the current i_{28} through the armature 28, and through the winding 45 as is hereinafter described.

Figure 4g shows the pre-excitation current i_{53} flowing through the winding 53 of the saturable transformer 47.

The current i_{53} is limited by the reactor 58 and, therefore, lags the voltage e_{23} by 90 degrees. The winding 53 is wound in opposition to the winding 46 of the saturable transformer 47 and, therefore, the current i_{53} appears to be reversed, i. e., leading the voltage e_{23} instead of lagging it. The sole purpose of the current i_{53} is to saturate the core 50 of the saturable transformer 47 at the beginning of the positive half cycle of the generator voltage e_{23} and to permit an early saturation of the core 50 at the end of the positive half cycle of the generator voltage e_{23} as is hereinafter described.

The times t_0 to t_8 indicated in Figures 5 and 6 are the same instants of time as those of Figure 4. A pre-excitation current i_{42} in Figure 5 is applied by the battery 41 in Figure 1 to displace the curve into the field of positive currents. i_{42} is a constant current which is very small compared to the main current i_{25} described above.

The curve as shown in Figure 5 is the dynamic flux current curve of the commutating reactor 44. Figure 6 shows a similar dynamic flux current curve of the saturable transformer 47. Again the times t_0 to t_8 are the same times t_0 to t_8 as in Figures 4 and 5. The pre-excitation current i_{53} is an alternate current and varies between the limits of i_{53} (+) and i_{53} (-). In the following explanation of the operation of the electromagnetic valve it is assumed that i_{53} is equal to i_{53} (+) during the time interval t_0 to t_3 and equal to i_{53} (-) during the time interval t_4 to t_8 . The zero line of i_{24} is therefore at two different places according to the time as shown in Figure 6. The appreciable slope of the magnetization curve of the saturable transformer 47 is due to the gap 51 in the core 50.

Consider the time t_0 at which the source voltage e_{23} becomes positive. The current i_{24} through the main line is 0, at this time, and the armature 28 is pulled away from the stationary contacts by the spring 34. The core 50 of the saturable transformer 47 is saturated by the current i_{53} and a free passage for the current exists then only through the selenium rectifier 55 which commences to carry the current i_{55} in phase with the generator voltage e_{23} as shown in Figure 4e. The current i_{55} is equal to the current i_{24} during the time interval t_0 to t_2 since all of the current that flows through the load 24 flows through the series connection 55. When the current i_{24} flowing through the winding 31 reaches a value high enough to produce a magnetic flux sufficient to attract the armature 28 to the fixed poles 26 and 27, the switch 25 closes. The armature 28 being very small and the attractive force being relatively high, the movement requires a time about $1/10,000$ th of a second which is negligible for the present considerations. The armature 28 closes at the instant t_1 and a current i_{25} commences to flow

through the switch 25. The current i_{25} , however, is limited by the commutating reactor 44 which has the winding 45 in series with the contacts of the armature 28.

Figure 5 shows this action having the flux of the core 43 plotted against the current i_{25} . After the time t_1 , the current i_{25} cannot rise to a value higher than i_M unless the flux is fully reversed from practically its negative minimum to its positive maximum. The current limit i_M can be made extremely small and hence protects the armature 28 from an excess of inrush current.

The reversal of the flux is due to the generator voltage e_{23} appearing substantially across the winding 45. The voltage e_{45} is shown as described above in Figure 4c. The time interval t_1 to t_2 is the time required to reverse the flux, after which the voltage e_{25} disappears and the current i_{25} is free to rise. Figure 4f shows how the current i_{25} is kept at the low value i_M during the interval t_1 to t_2 and rises suddenly at the time t_2 .

The area of the voltage e_{45} in the time interval t_1 to t_2 in Figure 4c is called the make-step. The make-step is a constant and is determined by the size and material of the core 43. Comparing Figures 4c and 4b, it is evident that the source voltage e_{23} is shifted from the switch voltage e_{25} to the load voltage e_{24} with an intermediate stage at the commutating reactor voltage e_{45} .

The rise of current, then, through the electromagnetic valve connected between points 21 and 22 is initiated by the selenium rectifier 55 and kept away from the armature 28 for a time interval t_0 to t_1 required to close a switch and for another time interval t_1 to t_2 required to increase the current through main winding 31 to a value sufficiently high to assure good contact pressure. This action takes place in a fraction of a millisecond and yet assures that the contact never closes incompletely or ever rebounds while a high inrush current flows. The current flowing through the selenium rectifier 55 closes the electromagnetic switch 25 without any current flowing through the switch 25 itself during the closing time. The operation is completely self-controlled and does not require any impulse control current or other outside action. It will, therefore, also work under extraordinary conditions and cease to operate instantaneously whenever the conditions of operation cease to exist.

After the time t_2 the current i_{25} through the armature 28 of the electromagnetic switch 25 rises to a value determined by the source voltage 23 and the load impedance 24 only, as shown in Figures 4f and 4d. The current i_{55} through the dry cell rectifier 55 decreases rapidly to zero since the rectifier 55 is short circuited by the armature 28. This condition is shown in Figure 4e where the current i_{55} reaches zero at the time t_3 .

As long as the current through the switch 25 and therefore through the winding 31 is maintained at an appreciable value, the switch 25 remains closed by the magnetic force due to the magnetic flux induced by the current i_{24} itself. Thus, there is no danger of the switch ever opening when current is flowing therethrough.

Figure 6 shows that the flux in the time interval t_0 to t_3 remains almost unchanged and so the saturable transformer 47 is inoperative during the whole closing cycle and has thus been disregarded in the discussion thereof.

The opening cycle of the electromagnetic switch 25 occurs in the interval between t_4 and t_8 when the pre-excitation of the saturable transformer 47 is reversed, as shown in Figures 6 and 4g. In Figure 6 the preexcitation is assumed to be i_{53} (—) and hence the zero line for i_{24} is shifted to the negative side. As i_{24} decreases towards zero, it passes through a point at which the core 50 of the saturable transformer 47 unsaturates. The current i_{24} at this unsaturating value is shown as i_{24} (5) in Figures 4d and 6. This value of current i_{24} (5) occurs at the instant of time t_5 . After the time t_5 the core 50 of the saturable transformer 47 is essentially equivalent to the core of a conventional transformer. In a conventional transformer the sum of ampere turns of all the

windings determines its magnetization and the electro-motive forces in its windings are directionally proportional to the number of turns. As the core 50 of the saturable transformer 47 becomes unsaturated, and its reactance rises to a high value, the voltage e_{46} across the winding 46 as shown in Figure 4b suddenly rises to the value of the source voltage e_{23} . The current i_{24} through the winding 46 decreases at a lower rate after the time t_5 . The voltage e_{46} on the winding 46 is transformed to the winding 52, and hence a current i_{55} , as shown in Figure 4e, commences to flow. As in any normal transformer, a decrease of the primary current corresponds to an increase in the secondary current and vice versa. Therefore, as the current i_{24} decreases, the current i_{55} increases. Both the line current i_{24} and the bypass current i_{55} flow through the armature 28 and the commutating reactor coil 45. The by-pass current i_{55} flows in the opposite direction to the current i_{24} and hence the resulting current through the armature 28 and the coil 45 is the difference of the two. The current i_{28} is shown in Figure 4f as decreasing at a much higher rate than i_{24} during the time interval t_5 to t_6 .

At the time t_6 the armature current i_{28} has reached a very small value i_B , which is practically zero and the by-pass current i_{55} is now equal to the main current i_{24} . In other words, the saturable transformer 47 displaces the line current i_{24} from the switch 25 to the dry cell rectifier 55 as soon as it becomes unsaturated. At the time t_6 the core 43 as shown in Figure 5 of the commutating reactor 44 unsaturates and the current i_{55} is henceforth fixed at the small value i_B . After the time t_6 the line current i_{24} flows through the dry cell rectifier 55 and the generator voltage e_{23} appears partly on the winding 46 of the saturable transformer 47 as shown in Figure 4b and partly on the winding 45 of the commutating reactor 44 as shown in Figure 4c. The line current i_{24} decreases slowly according to the slope of the left-hand curve in Figure 6 shown also as the lines in Figures 4d and 4e.

At a time t_7 the current i_{24} through remaining winding 31 of the electromagnetic switch 25 becomes too low to hold the armature 28 closed against the poles 26 and 27. The spring 34 pulls the armature 28 back against the bumper 37. This opening process is similar to the closing process in that it is a very rapid operation taking approximately $\frac{1}{10,000}$ th of a second. The armature 28 will interrupt the current i_{28} which is at that time t_7 equal to i_B , a current so small as to be practically negligible. Line current i_{24} which is now equal to the by-pass current i_{55} will decrease until it reaches zero at the time t_8 . The current i_{24} cannot reverse due to the non-symmetric characteristics of the dry cell rectifier 55 and, therefore, remains at the zero value.

The decrease then of the line current i_{24} demagnetizes the saturable transformer 47 which displaces the current i_{24} from the electromagnetic switch 25 to the dry cell rectifier 55. The current in the switch 25 is maintained at a very low value while it opens due to the suppression by the unsaturation of the commutating reactor. The remaining current i_{24} flows through the dry cell rectifier 55 until it ceases to flow naturally as it would in a normal dry cell rectifier. The opening of the switch 25 is completely self-controlled without any additional pulses or signals necessary.

The shape of the step due to the commutating reactor 44 follows essentially the shape of the hysteresis loop as shown in Figure 5 and may be corrected by straightener circuits as disclosed in application Serial No. 212,017 filed February 21, 1951.

The armature 28 of the electromagnetic switch 25 is constructed so as to have a natural frequency in the order of one kilocycle to be definitely mismatched with the frequency of the alternating voltage source 23. This mismatch is provided so that if the frequency of the

source 23 changes suddenly say from 60 cycles to 65 cycles, the armature 28 will commutate at 65 cycles and not tend to remain at its natural frequency. Another property of such a switch is the possibility of sudden start (zero to 60 cycles) or sudden stop without affecting the commutation.

The circuit of Figure 1 is only a modification of the present invention and may be improved upon in a variety of ways as shown for example in Figure 7. Figure 7 shows a single phase half-wave rectifier similar to that of Figures 1 and 2 with the exception that it provides for regulation of the direct voltage output as is hereinafter described.

Referring now to Figure 7, the alternating voltage source 123 is connected to the load 124 through the points 121 and 121A across the source 123 to the points 122 and 122A connected across the load 124. Connected in series between points 121 and 122 is the saturable transformer 147, the commutating reactor 144 and the electromagnetic switch 125. The saturable transformer contains two windings 146 and 152 which are wound on the core 150 having an air gap 151. The coil 146 is connected between point 121 and the coil 145 of the commutating reactor 144.

The commutating reactor 144 has a pre-excitation coil 142 which is biased by the battery 141. Both coils 142 and 145 are wound on the core 143. The other end of the coil 145 is connected to the conductor 160 of the electromagnetic switch 125. The other conductor 162 of the electromagnetic switch 125 is connected to the main coil 131 and thence to the point 122. The electromagnetic switch 125 has two poles 126 and 127 and an armature 128 mounted on a spring 134 and backed by laminations 137. The electromagnetic switch 125 also has a permanent magnet 163. The permanent magnet 163 is insulated from the remainder of the switch 125 by the insulator 164 and 165.

The contacts of the armature 128 are paralleled by a rectifier 166 in series with a parallel circuit containing a resistor 170 and a capacitor 171. The essential differences between the circuit of Figure 7 and that of Figure 1 resides in the absence of the pre-excitation winding 53 of Figure 1 and the stabilizing reactor 58 of Figure 1 from Figure 7. The flux current curve of the core 150 of the saturable transformer follows the curve shown in Figure 9 as compared to the Figure 6 which the core 50 of Figure 1 follows.

For obtaining the same change in flux during the opening period, the core 150 of the saturable transformer must have approximately twice the cross-sectional area of the core 50. The coils 53 and 58 in Figure 1, however, can be omitted.

Figure 8 shows the various voltage and current time curves of the circuit as shown in Figure 7. Figure 8b shows the voltage across the winding 146. As compared to Figure 4b, an additional voltage time area appears between the time t_1 and t_2 . This additional area causes an additional delay in the load voltage e_{24} so that its average voltage is lowered by 8 to 10%.

The by-pass or arc suppressor circuit containing the elements 170, 171 and 166 affords a passage for the residual current i_B shown in Figure 8g which flows through the armature 128 of the electromagnetic switch 125 at the opening time t_7 .

This small current i_B will charge the capacitor formed by the opening halves of the contact as this capacitor has an exceedingly small capacity. The voltage across this capacitor will rise to a very high value even with a very small current i_B . The capacitor 171 connected across the fixed contacts 169 and 162 of the switch 125 has a much higher capacity and, therefore, a much lower recovery voltage for the same current i_B . After the time t_8 , when the voltage e_{128} across the open contact rises suddenly to a high negative value, the selenium rectifier 166 prevents a reversal of current. When the

voltage e_{128} rises again in the positive direction at the time t_9 , the capacitor 171 is charged to this voltage. After the closing or make of the contact 128, at time t_1 , the capacitor 171 cannot discharge itself immediately as the selenium rectifier 166 is in opposition to the discharge current. In the time interval t_1 to t_7 , the capacitor discharges itself through the resistor 170.

The arc suppressor circuit acts as a capacitor with high capacity connected in parallel to the opening armature 128 and thus absorbs the residual current. On the other hand, it does not discharge itself through the contacts when it is closed and thus prevents contact damage due to an inrush current. When the direct current voltage is reduced by delaying the make point, the arc suppressor circuit does not carry a forward current or damage the contact with a capacitor discharge.

The direct voltage regulation is provided by the circuitry associated with a saturable reactor 180 having a core 181 and two windings 182 and 183.

The regulator coil 182 affords a delay for the make point of the contact 128 and thus a means to reduce the average direct current voltage output of the rectifier. The voltage e_{182} appearing across the coil 182 is required to magnetize the core 181. During this magnetization period the current i_{155} through the coil 182 and the selenium rectifier 183 is equal to the magnetizing current i_{M181} of the core 181 as shown in Figure 8f which is too small to operate the electromagnetic switch 125 through the coil 131. Only when the core 181 is fully saturated, the current i_{155} can rise freely and close the electromagnetic switch 125. The voltage e_{182} , shown in Figure 8c, reduces the load voltage e_{24} shown in Figure 8e by delaying the beginning of the conduction period from the time t_0 to the time t_1 .

The shaded area of Figure 8c is equal to the flux increase of the core 181 also shown as $\Delta\Phi_{181}$ in Figure 10. The size of $\Delta\Phi_{181}$ determines the amount of voltage lost to the direct current load by the make delay. The flux Φ_{181} does not reverse itself after the time t_8 unless a current i_{183} in Figure 10 is applied to the coil 183. When no current flows through the coil 183, the flux change $\Delta\Phi_{181}$ is very small and the make point is not delayed resulting in the output voltage of the rectifier being high. If a current i_{183} flows during the interval t_8 through the winding 183, in the direction given by the rectifier 184, connected from the coil 183 to a potentiometer 185, then the flux Φ_{181} is reversed to an extent depending on the amount of current. If Φ_{181} is reversed completely, the delay of the make point t_0 from the highest possible point t_1 is the longest possible and the rectifier works at the lowest possible direct current voltage. The flux reversal by means of coil 183 might be effected by several means, the example in Figure 7 shows a very simple one, a voltage proportional to the generator voltage e_{128} is taken from the voltage divider 185 and pushes a current through the coil 183 according to the position of potentiometer 185.

The current flowing through the winding 182 of the voltage regulator is the small current i_{155} and not the large current i_{129} flowing through the load; the regulator nevertheless controls the voltage and current through the load. Moreover, the control current i_{183} of the regulator is again much smaller than the current i_{155} , thus the ratio of control power to controlled power can be made to be one to thousand or better. The response time of the regulation, as described above, is approximately one-half cycle.

Another possibility for regulation is to apply the output current of a small magnetic amplifier, not shown, to the control windings 183. This modification would be important for high power rectifiers with multi-anode circuits, as it is possible by this means to vary the output voltage of the rectifier, and therefore its power, within the full range from zero to rated value, by means

of a control power which is exceedingly small and with an almost instantaneous response.

Instead of using a selenium rectifier 155 and a regulator coil 183, it is possible to use an electronic valve (not shown) where the voltage of the rectifier can be controlled by means of the grid control of the valve.

The regulator permits the output voltage of the rectifier to vary within a very wide range by means of a regulator coil 182 which acts like a magnetic amplifier with the added advantage of being exceedingly small and the speed of response attained is very high.

The premagnetization of the permanent magnet 163 in Figure 7 replaces the winding 40 of Figure 1. The permanent magnet 163 is insulated from the pole pieces 126 and 127 by means of thin sheets of insulation 164 and 165. An air gap 190 with very large area or low reluctance by-passes the permanent magnet 163. Thus a high short-circuit current in winding 131 merely increases the flux through the air gap 190 and does not demagnetize the permanent magnet 163.

The electromagnetic switch 125 can work without premagnetization, but then it requires a much higher current to operate.

In the foregoing description, a fundamental circuit was shown in Figure 1 and an equivalent circuit of slightly different design including voltage regulation was shown in Figure 7. A great many other variations of the fundamental circuit and of the basic circuit elements are possible.

The saturable transformer 47 in Figure 1 and 147 in Figure 7 consists of an easily saturable magnetic core 50 or 150 with an air gap 51 or 151. The properties of the magnetic cores 51 and 151 are shown in Figure 6 with pre-excitation and Figure 9 without pre-excitation. Figure 11 shows another design of a saturable transformer which offers the same properties when connected in a circuit as in Figure 1 or 7. Figure 11a shows the saturable transformer core 250 with an air gap 251. Wound around the core 250 is a winding 252, which is connected in series with an A.-C. generator 223 and an air inductor 258. The voltages on these three elements, i. e. the voltages e_{223} , e_{258} , e_{252} measured across the elements 223, 258 and 252, respectively, are shown in Figure 12a, 12b, and 12c.

The generator voltage e_{223} in Figure 12a is a pure sine wave. The air inductor voltage e_{258} in Figure 12b is equal to the generator voltage e_{223} as long as the core 250 is saturated during the intervals t_2-t_3 , and t_4-t_1 . In the intervals t_1-t_2 and t_3-t_4 , the core 250 is not saturated. Therefore, the coil 252 has a relatively high inductance as determined by the air gap 251. The generator voltage e_{223} therefore divides itself between the voltages e_{258} and e_{252} proportional to the inductances of coils 258 and 252. The inductance of coil 252 being higher than the inductance of coil 258, the voltage e_{252} is higher than the voltage e_{258} . The sharp cut off at the times t_1 , t_2 , t_3 , t_4 is due to the sudden saturation of the core 250. Whenever the coil 250 is saturated, the coil 252 has a negligible inductance and the voltage e_{253} equals the voltage e_{258} . The current flowing through this circuit reflects the sudden changes of inductance as during the intervals t_1-t_2 and t_3-t_4 when the inductance is high, the rate of change of the current is low, whereas during the times t_2-t_3 and t_4-t_1 when the inductance is low, the rate of change of the current is high. The current i_c is shown in Figure 12d.

Figure 11b shows a way of obtaining the same voltage and current curves with a saturable transformer core having no air gap. Highly saturable magnetic cores are usually made without air gap because the change in design required to make a core with air gap is highly detrimental to the magnetic properties, above all the ability to saturate fully at a low current. Figure 11b is almost identical to Figure 11a except that the air gap core is replaced by the core 260 without an air gap but with a

secondary winding 261 which is short-circuited by an inductor 263. For the time during which the core 260 is saturated, the circuits 11a and 11b are identical and therefore also the voltages and currents. When the core 260 is unsaturated, it exhibits the properties of a transformer with a very high mutual inductance and a very low leakage inductance. The inductance appearing on the primary is therefore the inductance 263 if the number of turns of coils 261 and 262 are equal to the primary coil. In such a case the circuits 11a and 11b are equivalent, the only difference will be a small internal current i_A flowing through the coils 261 and 263 which is shown in Figure 12e. Figure 11c shows a simplified way of representing the equivalence of the two circuits shown in Figures 11a and 11b.

Figure 13a shows a part of Figure 1, comprising the saturable transformer 47 and the commutating reactor 44. Figure 13b shows schematically the same circuit except that the core 50 of the saturable transformer has no air gap and is replaced by a reactor 270 as described above.

From Figure 1 and Figure 7 it is evident that the coils 46 and 45 have to carry the full load current and must therefore be made of heavy wire. It is possible to combine these two coils into one, as shown in Figure 13c. The new coil 271 is wound around two cores 272 and 273 which are equivalent to the cores 50 and 43 of Figure 13b. The secondary coils 274 and 275, similar to the coils 52 and 53 described above, are wound only around the core 272 and the coil 276, similar to 42 above, only around the core 273. As a potential point between the coils 46 and 45 is not available with this design, an additional primary coil 277 must be added in series with the coil 274. The voltage across the coil 277 is equal to the voltage across the winding 46 described above as it is wound only around the core 272, giving the correct potential to the start of winding 274. Practically, the arrangement shown in Figure 13c is perfectly equivalent to Figure 13a except that it is much cheaper to manufacture.

Single phase full wave rectifiers with true valves work either without overlap on capacitive or resistive load or with overlap on inductive load. The overlap is the time during which both valves are carrying current in the same direction with the current in the first valve decreasing and the second valve increasing. For resistive or capacitive loads the currents and voltages will be the same as for two single phase half wave rectifiers working in succession and for inductive loads the make of one valve occurs before the break of the preceding valve. Except for the faster make and break and a shortening of the make and break steps, the operation for inductive load remains unchanged. Practically, the rectifier is designed for this latter case which is true commutation and will then be amply sufficient for the first case. The transition from one mode of commutation to another occurs without disturbance and the electromagnetic valve thus exhibits the properties of a true valve.

A three phase rectifier circuit using three electromagnetic valves is shown in Figure 14. The operation of this rectifier is essentially the same as the single phase rectifiers described above in reference to Figures 1 and 7. The A. C. power supply (not shown) is connected to the A. C. terminals 1A, 1B, 1C. The terminals 1A, 1B and 1C are connected to a three phase transformer 300 which is connected in delta in the primary and in wye in the secondary. The neutral 301 of the transformer which is also the negative terminal of the rectifier is connected to the load 424. The secondary phases A, B and C of transformer 300 have voltages ea , eb , ec as their respective voltages against the neutral potential at 301.

In Figure 15a these voltages are plotted against time as dotted lines and are rectified by the rectifier as is hereinafter described to yield as composite D. C. voltage

11

shown as a heavy continuous line, also shown in Figure 15a. As the three voltages ea , eb , ec are equal in magnitude and occur during equal time intervals, the rectification takes place in three equal cycles during one cycle of the sine wave of the A. C. line voltage. The D. C. voltage then has a ripple of three times higher frequency than the A. C. frequency of the source.

For easier interpretation of the later figures, a simplified representation of the electromagnetic switch 125, shown in Figure 14, is used. The whole switch is represented in the dotted boxes 325 wherein is maintained only the armature 328, the exciter coil 331 and the iron core 326—326.

The phases A, B, C are connected through the commutating reactor windings 346 and electromagnetic switch 325 to the positive terminal 302.

The coils 346 are wound as described above on the transformer cores 350 and commutating reactor cores 343. The cores 350 also carry the secondary coils 352 which are paralleled by the coils 370. The coils 370 and 352 are connected to the main current carrying positive line 302 shown in heavy lines and to the control commutating reactors 400. The commutating reactors 400 have the coil 382 and 383 wound on the cores 381. The coils 382 connect the coils 352 to the electromagnetic switches 325 through the rectifiers 355. The cores 343 are premagnetized by the windings 342 which are connected in series between main current carrying lines 301 and 302. The cores 350 are pre-magnetized by the windings 353 each connected through an inductor 358 to the negative main line 301 and to a different phase load A, B or C, than the phase the core 350 is in. The choke or inductor 353 is connected to the preceding phase, having the preexcitation voltage leading by 120 degrees to obtain a favorable phase relationship for the preexcitation current.

Whenever the voltage of a phase exceeds the voltage on the direct current load by a certain positive amount, the electromagnetic switch of this phase will close. Whenever the current through an electromagnetic switch 325 decreases towards zero, the switch will open, operating exactly the same way as a half wave valve described above in reference to Figures 1 and 7.

The similarity of the operation is seen by comparing Figures 8 and 15; taking into consideration that Figure 8 concerns a half wave rectifier operating on a mostly resistive load whereas Figure 15 concerns a three phase rectifier operating on a load 424 with exceedingly high inductance shown as 425 in Figure 14. A high inductance such as 425 inserted into the direct current circuit will maintain the direct current almost perfectly constant. The sum of the phase currents ia , ib , ic , is then constant where each of these currents consists of a series of pulses with a flat top equal to the direct current. Due to the three phase rectification, the direct voltage is more continuous, as shown in Figure 15a as a solid line than the voltage $e124$ in Figure 8. During the changeover from one phase to another, the direct voltage assumes the average voltage of both phases as during the times $t3-t4$ and $t5-t6$ in Figure 15 which is a common property of all rectifiers.

In Figure 15c, the pre-excitation current $i353a$ of the saturable transformer of phase A is shown as a dotted line. Comparing Figures 15c with 15a shows that $i353a$ is leading in phase on the voltage ea of phase A. Figure 15c also shows the voltage $e346a$, which is the voltage across the common winding 346 of the phase A. In the time interval $t1-t4$, the pre-excitation current $i353a$ is positive and keeps the transformer core 350 saturated in the forward direction, therefore, the transformer core 350 must be fully demagnetized and reversed before the line current can decrease to zero. A longer break step is then caused during the intervals $t6-t9$, due to the cores 350 and 353. These steps are represented by the voltage time areas enclosed by the voltage 346a in Figure

12

15c, which is the commutating reactor voltage of the phase A.

The commutating cores 343 are pre-magnetized with a direct current flowing through winding 342 and equalized by the choke 426. The direct voltage is taken from the output of the rectifier itself.

When the voltage ea of phase A reaches a positive value high enough to overcome the direct voltage between 301 and 302 at time $t0$ in Figure 15, a current $i355a$ starts flowing through the windings 352, 370, 382, the selenium rectifier 355 and the main winding 321 of the electromagnetic switch 325. Due to the easily saturable core 381, the current is limited to a very small value approximately a few milliamperes. The entire voltage difference between the point A and the point 320 appears on the winding 382 as the voltage $e382a$ shown in Figure 15D. This voltage also appears across the open contact 328 of the armature shown as $e328a$ in Figure 15B. When the core 381 of the regulator coil 382 finally saturates, the voltage $e382$ disappears and the current $i355a$ rises freely as is shown in Figure 15G at the time $t1$. The current $i355a$ also flows through the windings 321 of the electromagnetic switch 325 and effects the closing of the switch 325 at the time $t2$ when it reaches the critical value to close the switch. A current $i328a$ starts flowing through the winding 346 and the armature 328 demagnetizing the commutating core 343. During the demagnetizing period of the core 343 or the make step which is the time $t2-t3$, the voltage difference between the points A and 302 appears on the winding 346 shown as $e346a$ in Figure 15C. The current $i328a$ is maintained at the value of the magnetizing current of the core 343 which is less than one ampere as is shown in Figure 15F. During this time the current $i135a$ still rises because the voltage difference between A and 302 still exists. At the time $t3$, the core 343 is saturated and the current $i355a$ rises rapidly to the value of the full direct current as shown in Figure 15F whereas $i355a$ decreases toward zero as shown in Figure 15G. The sum of $i328a$ and $i355a$ is the line current ia shown in Figure 15E.

The rise of current in phase A is delayed by the time required to saturate, by the voltage $e382$ the regulator core 381. Depending on the amount of flux to be changed in the core 381, the commutation between the phases is more or less delayed giving a lower or higher average direct voltage output. This voltage regulation can be effected by means of the flux reversal of the core 381 which is obtained with an auxiliary current $i383$ in the coil 383. The coils 383 are connected to selenium rectifiers 430 which prevent the current $i383$ from reversing through limiting resistors 431. The rectifiers 430 are connected to the secondaries 432 which control the amount of flux reversal to be effected. It is the phase voltage ea which is essentially used to perform the flux reversal.

A source 436 of a direct current $i436$ of very low power (approximately one watt) essentially determines the direct current output voltage of the rectifier. The source 436 feeds through a resistor 55 which limits the control current $i436$ to the primary windings 434 of each phase. The windings 432 and 434 are wound on the cores 433 made of an easily saturable material. When the control current $i436$ is zero, the auxiliary current $i383$ is limited in the forward direction only by the resistor 431. A high current $i383$ flows during the time that the phase voltage ea is negative, which reverses the flux of the core 381 and thus delays the current $i355a$, delaying in turn the closing of the switch 325 so that the rectifier delivers a very small direct voltage or none at all.

When the control current $i436$ is high enough to magnetize the cores 433 which require only a very small current, the auxiliary current $i383$ in turn is delayed by the flux reversal of the cores 433. The current $i383$ is unable to rise to a sizeable value during the time that the phase voltage ea is negative, and therefore the magnetic

flux in the core 381 remains unchanged. This in turn permits the current i_{355a} to rise immediately when the phase voltage ea exceeds the direct voltage, thus closing the switch 325 and allowing the highest possible direct voltage output of the rectifier.

It is obvious that an intermediate amount of the control current 436 permits regulation of the output voltage of the rectifier to any desired value.

The above described procedure is similar to the one described by means of Figures 7 and 8, except that a new core 433 was introduced. The control core 433 permits the regulation of the rectifier by means of a direct current instead of a pulsed current and requires a control power which can be made as low as one millionth of the power output of the rectifier.

The aggregate of the control coil 433 and associated windings together with the selenium rectifier 430 forms a self-saturating magnetic amplifier. Similarly, the aggregate of the regulator coil 400 except that its output current i_{355a} appears as double pulses acts as an amplifier. The direct current control is not used immediately on the regulator coil 400, as it would greatly hamper the correct interruption of the contact by introducing a flux reversal during the time when the switch 325 is closed and i_{355a} is zero.

Comparing the output current of the rectifier to the control current i_{436} it appears that it exhibits the properties of an amplifier with the advantages of a high efficiency, small weight as the control elements are submitted to small currents only, fast response and an exceedingly high rate of amplification.

To open the electromagnetic switch, the same procedure is applied as in the examples described above in reference to Figures 1 and 7. The current ia in the phase A is equal to the direct current of the output until phase B starts carrying current by the same process as described above for phase A. When the current ib in phase B rises to the full value of the direct current during the time t_5 to t_6 , the current in phase A decreases correspondingly, as shown in Figure 15E. At the time t_6 , the current ia has reached the point at which the saturable transformer core 350 unsaturates. The commutating voltage between the phases A and B appears on the winding 346 of phase A, shown as e_{346a} in Figure 15C. The current ia is limited by the inductance of the saturable transformer core 350 and decreases in a less rapid slope as shown in Figure 15E. The voltage e_{346a} is transformed into the winding 352 which has more turns than the winding 346 and is so proportionally higher. The transformer voltage is the cause of a new rise of the current i_{355a} as shown in Figure 15G. Inasmuch as i_{355a} is rising, the current through the armature 328a decreases as shown in Figure 15F. At the time t_7 , the current i_{328a} reaches zero, and now the core 343 unsaturates as well, keeping i_{328a} at the zero value, as shown in Figure 15F. The current i_{355a} through the parallel path is now equal to the line current shown in Figures 15E and 15G and continues to decrease until it reaches zero at the time t_9 . At the time t_8 the line current ia which is i_{355a} reaches the limit of the holding current of armature 328 by means of the coil 321 and interrupts only the small magnetizing current allowed by the core 343 in coil 346.

The opening of the switch 325 always happens when there is no current flowing through it and at the natural cut off time of the electromagnetic valve.

The examples treated in the foregoing description are only a few of many possible connections as, for example, bridge connections, multiphase connection with interphase transformers, etc., may be used.

It is also possible to replace the selenium rectifier 355 in all these examples by a gas discharge tube, and control the output voltage of the rectifier by means of the grid control of this tube.

As described above in reference to Figure 13a, the sat-

urable transformer 47 and the commutating reactor 44 can be altered, without affecting their operation, to simplify manufacture. The core 50 of the saturable transformer, with the air gap, presents an almost unsurmountable obstacle, as it must be made of an easily saturable magnetic material and also have an air gap of definite dimensions. If an air gap is cut into such a core, or the core is made in two halves and assembled, most of the desirable characteristics of the material are lost.

In order to obtain the desired magnetic characteristic, the core 50 should be a toroid, as described above. Windings around such a toroidal core are difficult and therefore expensive to make. It is possible to reduce the number of coils utilized in the system. These alterations are shown in Figure 16.

In Figure 16, the coils 352 and 353 of Figure 14 are combined into one coil 454 and the former coil 370 has as its equivalent a transformer 450. The transformer 450 has a primary winding 457 and a secondary winding 455 with air gaps 460 in the iron core 458. The air gaps 460 limit the inductance of the secondary 455 to the same value as of coil 370 in Figure 14. The coil 456 and the transformer 450 are mounted together and provided with adjustable air gaps 460 and 463. The adjustable air gaps 460 and 463 permit the amount and the slope of the current i_{355a} , which is shown in Figure 15G, to be adjusted. These adjustments are required to compensate for the individual differences of the electromagnetic switches.

Comparing the circuit of Figure 16 to the circuit of Figure 1, it is apparent that the coils 46 and 45 of Figure 1 have been merged into coil 450 in Figure 16; the coils 52 and 53, together with the air gap 51, have been replaced by a single coil 454. The coil 42 becomes coil 453 and the coil 58 becomes coil 456. The transformer 450 is an additional unit, but is small and easy to manufacture and so its expense is insignificant as compared to the savings in the other items.

Referring now to Figure 17, a source of alternating voltage 500 provides a direct current to a load 527 through an electromagnetic valve 570 formed by the movable armature 519 and the fixed contacts 515 and 517. The fixed contacts 515 and 517 are identical with the two legs or poles of the electromagnetic valve 570. An armature 519 is fastened to a spring 520 which is supported by insulators 521.

A combined commutating reactor 571 having a coil 508, a reactor core 507 and a saturable transformer core 504 is connected in series with the electromagnetic valve 570. The reactor core 507 has a pre-excitation winding 506 which is supplied with a small direct current from the battery 505. The saturable transformer core 504 has a secondary winding 503 which is connected to a transformer 572 having an air gap 502 and a current limiting reactor 501.

A regulator 573 is connected in series between the electromagnetic valve 570 and the commutating reactor assembly 571. The regulator has a regulator coil 512 with a main current saturating coil 509, a core 510 and a control coil 511. The control coil 511 is supplied with a direct current from an external source 513. One end of the regulator coil 512 is connected to the coil 503, described above, and the other end to the electromagnetic valve 570, as is hereinafter described.

When a direct current of sufficient magnitude flows through the coil 514 or the coil 518, which are wound on the poles 515 and 517, the armature 519 is pulled against the poles or fixed contacts 515 and 517.

A permanent magnet 516, which is clamped between the magnet poles 515 and 517, provides a constant magnetic flux for polarization, in order to render the electromagnetic switch 570 more sensitive.

A dry cell rectifier 522, which may be selenium, and the capacitor 523, as shown in Figure 17, is connected

across the switch 570 and corresponds exactly to the parts 166 and 171 of Figure 7. They form a Spark Suppressor circuit which has a low impedance immediately after the opening of the armature 519, a higher impedance when the voltage is reversed against the direction of the direct current, and also a high impedance for prolonged application of the forward voltage which occurs when the closing time of the electromagnetic valve is delayed for output voltage control.

The junction of the rectifier 522 and the capacitor 523 is connected to a discharge resistor 524, which corresponds to resistor 170 in Figure 7. The resistor 524 is, in turn, connected to a source of direct voltage 525.

When the armature 519 is closed and carrying the load current, the battery 525 and the dry cell rectifier 522 carry a very small forward current. This current is sufficient to overcome the initial forward voltage drop of the dry cell rectifier 522, and provide a small negative charge to capacitor 523. When the armature 519 opens, the residual forward current flowing through it will find a Spark Suppressor, parallel path 522 and 523 which has an exceedingly low resistance, which is much lower than such a circuit without the battery 525. Since the forward potential barrier of the dry cell rectifier 522 is very small (i. e. one fiftieth of the inverse voltage), and the current required to overcome it is also very small (i. e. one tenth of an ampere); the required direct current supply 525 can be made very small and inexpensive.

In order to save the material and expense of a coil of heavy wire with many turns, an additional coil 518, described above, is wound on the magnet pole 517. The coil 518 carries only the current flowing through the parallel valve 526, shown as i_{55} in Figure 4e and so can be made from very thin wire. The coil 514, however, carries the current flowing through the armature 519, shown as i_{28} in Figure 4f, which is high enough to provide enough magnetization even if coil 514 has only a few turns. The coil 514, therefore, is made of heavy wire, but has only a few turns.

In the Figure 7 the regulator core 181 is demagnetized by a coil 183, in which flows a pulsed direct current. This control current must be unidirectional to provide only a flux reversal, and variable in amplitude according to the desired output voltage. It must also be zero during the time the load current i_{128} in Figure 8 flows through the armature 128 (Figure 7) and not through the valve 155. Using a continuous direct current would be much simpler and cheaper. A direct current, however, must be prevented from reversing the flux of the regulator core 181 during the time the load current flows through the line and the armature 28, or the de-saturated core 183 would prevent the current i_{55} from flowing at the end of the cycle and therefore prevent the valve from opening.

In Figure 17 the regulator coil 512 with the core 510 and the control coil 511 corresponds to coil 182 in Figure 7. An additional coil 509 connected in series with the main line of current and having only a few turns, magnetizes the core 510 with the main current itself. The main current will overcome the demagnetizing effect of the control current, during the time the main current flows through the armature 519. Thus it is permissible to operate the control coil 511 with a continuous direct current which may be provided by any desired external source 513.

Although the modification as shown in Figure 17 permits an appreciable saving of space, material and lost energy, the principle of operation of the electromagnetic valve remains unchanged.

When the voltage of the generator 500 is positive in the left hand terminal and negative in the right hand terminal, it is positive in direction of the flow of current through the electromagnetic valve 570. If this voltage causes a current in the circuit, the direction of the current will be positive according to the arrow as shown.

When the voltage of generator 500 turns from the negative direction into the positive direction, a current will start flowing through the coils 503, 512, 518, the rectifier 526 and the load 527.

This current is limited by the impedance of the coil 512 to a very small value, which is too small to operate the electromagnetic switch 570. The voltage of the generator 500 appears on the coil 512 which is the highest impedance in the circuit and remains there until the core 510 saturates. The time interval required is given by the amount of flux which was displaced by the control current in the coil 511 during the previous half cycle. In other words, the starting moment for the flow of current through the magnetic valve 570 is determined by the saturation of the core 510, which in turn is determined by the small direct control current flowing through the coil 511.

If the control current is zero, the core 510 remains always saturated in the positive direction, and therefore no delay of current flow in coil 512 will ensue and the output voltage will be the highest obtainable. If the control current is equal to or higher than the magnetizing current of the regulator core 510, then the full delay which is proportional to the iron area of the core 510 will ensue. By proper design, this delay can be made sufficient to stop the operation of the rectifier altogether, and the output voltage will be zero. For any intermediate control current, the output voltage will assume an intermediate value.

As the main winding 512 of the regulator coil carries only a small rms current, it can be wound with small wire. Thus, a relatively small coil will control the voltage and hence the power of a much larger system.

Once the core 510 is saturated, the impedance of the coil 512 becomes very low and the current through the circuit increases rapidly. When it reaches a value high enough to magnetize (by means of coil 518), the poles 515 and 517, the armature 519 is moved establishing a low resistance path through the main line.

The current through the main line cannot increase immediately as it is limited by the impedance of the coil 508, due to the non-saturated core 507. Only after saturating core 507 can the main current rise freely. The delay required to saturate core 507 is called the make step, which prevents excessive current through armature 519 before it is fully seated.

During the time period described above, the transformer core 504 is saturated by a current flowing from transformer 572 into coil 503 and hence does not contribute to the impedance of the coils 503 and 508.

Once the armature 519 is firmly closed and the core 507 is fully saturated, the current through the main line can rise to the full value determined only by the voltage of 500 and the impedance of 527. The parallel circuit through the elements 503—512—518 and 526, which initiated the operation and which carried enough current through coil 518 to close the electromagnetic switch 570, is now short circuited. Thus the current in coil 514 rises while it decreases in coil 518. The ultimate value of the current in coil 514 is higher than the current in coil 518, as the main line has a much lower impedance requiring fewer turns of the coil 514. With increasing line current, the force on the armature 519 increases, reducing the contact resistance.

The coil 506 fed with a direct current from the source 505 pre-magnetizes the core 507 in such a way as to have a very small or negligible magnetizing current in the main coil 508. Thus the inrush current through 519 after the make and the residual current after the break can be kept at a very small value. It is possible to use the same methods as described in my application No. 212,017 with regards to straightener circuits to further reduce these currents.

When the positive current generated by the alternate

voltage source 500 declines and reverses its direction into the negative, a break or interruption occurs.

Due to the alternating current pre-excitation by means of the coil 503, the transformer 572 and the reactor 501, the core 504 will de-saturate, when the current in the coil 508 declines enough to make the ampere turns of 508 and 503 in core 504 equal and opposite. This de-saturation limit of current is made high enough that the armature 519 is still held firmly by the magnetizing effect of coil 514 when the limit is reached.

The core 504 upon de-magnetizing becomes the core of an almost ideal transformer with negligible magnetizing current and very small leakage reactance due to the high quality material. A voltage drop appears suddenly on coil 508 and is transformed proportionally to the number of turns into the coil 503. This voltage drop is in opposition to the direction of the current, as the coil 508 is an inductive load and the current is decreasing. Hence the lower end of coil 508 and the left hand end of coil 503 become positive and the upper end of coil 508 and the right hand end of coil 503 become negative. The coil 503 has a higher number of turns than coil 508 and the voltage of coil 503 is thus proportionally higher than on 508. The net voltage, therefore, being applied to the closed circuit 503-512-518-526-519-514-509-508, is positive in the direction of this enumeration and will be the cause of a rising current of the same direction. This rising current is opposed by very little impedance, as the cores 507, 510, 515 and 517 are saturated by the still appreciable current through the main line (500-508-509-514-519-527) and so rises very rapidly. The rising current of the closed loop and the main current oppose each other in the main line of current (508-509-514-519), bringing the total current in these elements rapidly to zero. When reaching zero, however, the resulting current cannot reverse due to the de-saturation of core 507 which assumes an extremely high impedance and "freezes" the main line current at a very low value. The line current now passes entirely through the path 500-503-512-518-526-527. Through the armature 519 flows only a very small residual current which is due to the difference between the magnetizing current of the core 507 and the pre-excitation due to the coil 506, which can be reduced to a few milliamperes. When the line current decreases to a value too low to hold in the armature 519 by means of the coil 518, the armature 519 opens the main circuit. For the small residual current a low impedance by-pass through the dry cell rectifier 522 and the capacitor 523 permits an easy flow without giving cause to an unduly high recovery voltage between the armature 519 and the fixed contacts 515 and 517.

The current through the line will decrease to zero, but cannot reverse because the armature 519 is open, and the small rectifiers 526 and 522 pass only a very small inverse current.

As described for the previous circuits, the make procedure is dependent only upon the voltage across the valve, and the break process only upon the current through the valve. Both operations require a very short time in the order of $\frac{1}{10,000}$ of a second.

As described above, Figure 17 shows a circuit which is equivalent to the ones shown in Figures 1 and 7. It has the advantage, however, to be easier to manufacture, to regulate and to adjust than the previous circuits. Moreover, it has the additional advantages of a lower recovery voltage across the opening contact which will result in a longer contact life. Still another advantage is the use of less material with a smaller power loss, a higher output voltage and a better power factor.

The operation described above for the single phase half wave rectifier of Figure 17 remains practically the same if the several identical units are connected together to form a multiphase rectifier. In Figure 18 a three phase half wave rectifier is shown in which the same elements

as in Figure 17 are repeated three times. The operation is identically the same as the one of the three phase circuit shown in Figure 14 with the voltage and current curves of Figure 15. The improvement from Figure 14 to Figure 19 is the greater ease of manufacture, the smaller number of critical parts (like non-linear reactors and their windings), smaller losses, smaller weight and higher output voltage when working from the same transformer. It is also possible with the latter circuit to obtain correct operation with a lower accuracy of the magnet-spring 520 and a higher over-all contact life due to the lower recovery voltage and the greater ease of adjustment.

From the basic circuits shown on Figures 17 and 18 a great number of variations and convenient re-arrangements are possible, according to the requirements of the different practical applications.

Figure 19 shows a circuit which is derived from Figure 17. Instead of using a regulator coil 512 with the core 510 and the auxiliary windings 509 and 511, in series with a rectifier 526, the circuit of Figure 19 uses a thermionic tube 559. This tube also replaces the capacitor 523 of the previous circuit. The circuitry of Figure 19 has a transformer 580, a commutator unit 581 and an electromagnetic switch 582, similar to the elements 572, 571 and 570, respectively, of Figure 17.

The main current path of the rectifier is now in the positive direction 540-547-548-549-554-551-557. The by-pass circuit which carries the current while armature 554 closes or opens is through the elements 540-543-552-558-559 and 557. The rectifier 553 is the spark-suppressor by-pass connected to the electromagnetic switch 582. The other end of the rectifier 553 is connected through an anode resistor 558 to the anode 560 of the thermionic tube 559. The grid 561 of the tube 559 is connected through the grid resistor 563, saturable reactor 565 and resistor 564 to the transformer 568. The cathode 562 of the tube 559 is also connected to the transformer 568. The secondary voltage of transformer 568, together with the saturable reactor 565 and the resistor 564 form an alternating current grid voltage supply with variable phase angle. Through the primary coil 565b of reactor 565 flows a direct current provided by a source 569 which is stabilized by a choke 567 and limited by a resistor 566. When the direct current is high, the inductance of the secondary coil 565a of reactor 565 is low and when the current is low, the inductance of the secondary coil 565a of reactor 565 is high. In the present modification the grid voltage is practically proportional to the voltage of source 540 and the tube 559 behaves like a diode. By increasing the direct current, the secondary inductance of coil 565b is decreased further delaying the grid voltage, which in turn delays the firing point of the tube 559. Thus the direct current provided by the source 569 controls the firing time of the tube 559, which controls the firing of the rectifier and thus the output voltage.

When no current flows through the windings 548 or 552 and the armature 554 is open, the voltage of source 540 appears on the tube 559. When this voltage becomes positive, the tube 559 fires, unless the grid voltage is negative, in which case the tube fires only when the grid voltage also turns positive. The anode current of the tube flows then through the elements 540-543-552-558-559-557. This current magnetizes the coil 552 which in turn attracts the armature 554. The current in the main line is limited for a short time by the core 545, until it is saturated, after which it rises to its full value. The tube then extinguishes, as it becomes short circuited by the path 547-548-554.

The saturable transformer core 544 which was saturated during the make operation will unsaturate when the line current declines. A voltage drop appears on coil 547 and is transformed to coil 543. The difference of these voltages appears on the tube 559 which is the only open point in the circuit 543-552-558-559.

554—548—547. As the grid voltage of the tube 559 is positive, it will fire as soon as the anode voltage is high enough. A current then commences to flow in the above described closed circuit, rising sharply until the full current of the main line is shifted over to the by-pass circuit. The main line current now is limited by the reactance of the de-saturating core 545 in coil 547. The residual current flowing through the by-pass circuit containing the tube 559 will decrease to zero without being able to reverse due to the rectifying characteristic of the tube 559. Any residual current flowing through armature 554 at the time of opening will be displaced to rectifier 553 without causing an excessive recovery voltage.

The advantage of this circuit over the circuit of Figure 17 is the saving in expense and material of the saturable core 510 and its windings. On the other hand a thermionic tube is needed with its grid supply and its heating power supply. These parts are, however, relatively small.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. An electromagnetic control circuit comprising a source of alternating current; an output circuit; a contact element forming a switch, said switch being in series with said source and said output circuit; a rectifier in parallel with said switch; a commutating reactor having a main coil in series with said switch and said source of alternating current, and a reactor core; a transformer, said transformer having a transformer core and a secondary coil, said main coil being wound on said reactor core and said transformer core acting as a primary for said transformer; a first winding for said switch; said secondary coil of said transformer being in series with said rectifier and said first winding; and said first winding responsive to the energization of said rectifier and said commutating reactor and said transformer for operating said switch.

2. An electromagnetic control element comprising a commutating core; a transformer core; a main winding wound around said commutating core and said transformer core; a secondary winding wound on said transformer core; and a biasing winding wound on said commutating core, said biasing winding controlling the change in saturation of said cores and the energization of said secondary winding.

3. An electromagnetic control circuit comprising a source of alternating current; an output circuit; a contact element forming a switch, said switch being in series with said source and said output circuit; a rectifier in parallel with said switch; a commutating reactor in series with said switch and said source of alternating current; and means responsive to the energization of said rectifier and said commutating reactor for operating said switch, said means having a regulator coil in series with said rectifier, said regulator coil being energized during the opening and closing operations of said switch, said switch having two magnetic poles and biasing means basing said contacts to opening position when said means is not energized; a first winding for controlling the operation of said switch; said first winding connected in series with said regulator coil, said rectifier and said source of alternating current.

4. An electromagnetic switch regulator comprising a regulator core and an electromagnetic switch; a regulator coil wound on said regulator core; said regulator core being a highly saturable material; a control coil wound on said regulator core; and a main coil wound on said regulator core, said regulator coil being constructed of thin wire and said main coil being constructed of heavy wire, said regulator coil limiting a rising current through said

regulator to a value insufficient to operate said electromagnetic switch until said regulator core saturates, the energization of said control coil determining when said regulator core saturates, said main coil preventing a demagnetization of said regulator core during the flow of current in said main coil.

5. An electromagnetic control circuit comprising a rectifier and a regulator coil in series; a source of alternating current; a contact element forming a switch; an output circuit; said switch being in series with said source and said output circuit; said rectifier and regulator coil being connected in parallel with said switch; first means operable by energization of said control circuit closing said contact element; and second means in series with said switch energized upon the closing of said contact for maintaining said contact closed.

6. A self-controlled rectifier comprising a source of alternating current; an output circuit; an electromagnetic switch; a combined commutating reactor; and an electromagnetic switch regulator; said electromagnetic switch comprising two magnetic poles; a movable armature; a spring member biasing said armature; a main winding wound on one of said magnetic poles and a control winding wound on the other of said magnetic poles, a permanent magnet sensitizing said switch by supplying a constant magnetic flux for polarization, said control winding being energized before the opening and closing of said electromagnetic switch; said combined commutating reactor having a reactor core; a transformer core; a main commutator winding wound around said reactor core and said transformer core; a secondary winding wound on said transformer core; a pre-excitation winding wound on said reactor core; a direct current source connected to said pre-excitation winding, said pre-excitation winding receiving a direct current from said direct current source and pre-magnetizing said reactor core so that said reactor core requires a negligible magnetizing current from said main commutator coil, the residual current through said main commutator winding after make and before break being restrained to a small value; said electromagnetic switch regulator comprising a regulator core; a regulator coil wound on said regulator core; a control coil wound on said regulator core; and a main coil wound on said regulator coil, said regulator coil being constructed of thin wire and said last mentioned main coil being constructed of heavy wire, said regulator coil limiting a rising current through said regulator to a value insufficient to operate said electromagnetic switch until said regulator core saturates, the energization of said control coil determining when said regulator core saturates.

7. A self-controlled rectifier comprising an electromagnetic switch; a combined commutating reactor; and a tube regulating circuit; said electromagnetic switch comprising two magnetic poles; a movable armature; a spring member biasing said armature; said magnetic poles electrically insulated from each other, said magnetic poles forming stationary contacts for engagement by said movable armature; a heavy few turned winding wound on one of said magnetic poles; and a thin many turned winding wound on the other of said magnetic poles; and a permanent magnet clamped between said magnetic poles, said permanent magnet sensitizing said switch by supplying a constant magnetic flux for polarization, said thin many turned winding being energized before the opening and closing of said electromagnetic switch, said commutating reactor unit having a reactor core; a transformer core; a main winding wound around said reactor core and said transformer core; a secondary winding wound on said transformer core; a pre-excitation winding wound on said reactor core; a direct current source connected to said pre-excitation winding, said pre-excitation winding receiving a direct current from said direct current source and pre-magnetizing said reactor core so that said reactor core requires a negligible magnetizing current from said main coil, the residual current through

said main winding after make and before break being restrained to a small value, said tube regulating circuit comprising a direct current controlling source; a thermionic tube; and a connection across said commutating reactor unit, said direct current source controlling the firing time of said thermionic tube which in turn controls the operation of said electromagnetic switch and thus the output voltage from said switch.

8. A control circuit comprising a rectifier; a pair of contacts connected across said rectifier; an electromagnet controlling the opening and closing of said contacts; and a main winding and control winding for said electromagnet, said control winding being in series with said rectifier and effecting the closing of said contacts at the commencement of current flow through said rectifier, said main winding being in series with said contacts and energized by the closing of said contacts to maintain said contacts closed.

9. A control circuit comprising a rectifier; a pair of contacts connected across said rectifier; a regulator coil; an electromagnet controlling the opening and closing of said contacts; and a main winding and control winding for said electromagnet, said control winding being in series with said rectifier and effecting the closing of said contacts at the commencement of current flow through said rectifier, said main winding being in series with said contacts and energized by the closing of said contacts to maintain said contacts closed, said control winding being energized through said regulator coil, said regulator coil and said rectifier forming a magnetic amplifier.

10. A control circuit comprising a rectifier; a pair of contacts connected across said rectifier; a regulator coil; an electromagnet controlling the opening and closing of said contacts; and a main winding and control winding for said electromagnet, said control winding being in series with said rectifier and effecting the closing of said contacts at the commencement of current flow through said rectifier, said main winding being in series with said contacts and energized by the closing of said contacts to maintain said contacts closed, said control winding being energized through said regulator coil, said regulator coil and said rectifier forming a magnetic amplifier, said contacts being opened by the reduction of current therethrough.

11. A control circuit comprising a rectifier; a pair of contacts connected across said rectifier; a regulator coil; an electromagnet controlling the opening and closing of said contacts; and a main winding and control winding for said electromagnet, said control winding being in series with said rectifier and effecting the closing of said contacts at the commencement of current flow through said rectifier, said main winding being in series with said contacts and energized by the closing of said contacts to maintain said contacts closed, said control winding being energized through said regulator coil, said regulator coil and said rectifier forming a magnetic amplifier, said contacts opening when the current therethrough reduces to zero.

12. An electromagnetic control circuit comprising an electromagnetic switch having a main and a control winding; a commutating reactor having a main and a biasing winding, said main winding of said commutating reactor being in series with said main winding of said electromagnetic switch; a rectifier being in series with said control winding of said electromagnetic switch; said rectifier and said control winding shunting said main windings of said commutating reactor and said electromagnetic switch, said biasing coil of said commutating reactor causing said main winding of said electromagnetic switch to be energized after the energization of said control winding and the closing of said electromagnetic switch.

13. A self-controlled rectifying circuit for a plurality of phases comprising for each phase an electromagnetic switch; a saturable transformer; a commutating reactor; a control circuit; and a rectifier, said saturable transformer effecting a decreasing current having a relatively

large maximum value to flow through said rectifier, said rectifier being connected in parallel with said electromagnetic switch and said commutating reactor maintaining the current at a relatively low value until said electromagnetic switch opens, said control circuit comprising a plurality of commutating reactors, each commutating reactor effectively controlling a circuit having a larger current flow than the current which controls it so that amplification takes place.

14. An electromagnetic control circuit comprising a source of alternating current; an output circuit; a contact element forming a switch, said switch being in series with said source and said output circuit; a rectifier in parallel with said switch; a commutating reactor having a main coil in series with said switch and said source of alternating current, and a reactor core; a transformer, said transformer having a transformer core and a secondary coil; said main coil being wound on said reactor core and said transformer core acting as a primary for said transformer; a first winding for said switch; said secondary coil of said transformer being in series with said rectifier and said first winding; and said first winding responsive to the energization of said rectifier and said commutating reactor and said transformer for operating said switch; said secondary coil of said transformer being short circuited by a second secondary winding of a second transformer; said second transformer providing pre-excitation current for said secondary winding of said transformer through said second secondary winding.

15. An electromagnetic control circuit comprising a source of alternating current; an output circuit; a contact element forming a switch, said switch being in series with said source and said output circuit; a rectifier in parallel with said switch; a communicating reactor having a main coil in series with said switch and said source of alternating current, and a reactor core; a transformer, said transformer having a continuous transformer core and a secondary winding, said main coil being wound common to the reactor core and said continuous transformer core; said main coil acting as a primary winding for said transformer; said secondary winding of said transformer being in series with said rectifier; means responsive to the energization of said rectifier, said communicating reactor and said transformer for opening said switch; said means having a regulated coil in series with said rectifier and said secondary winding; said regulator coil being energized prior to the opening and prior to the closing operation of said switch.

16. An electromagnetic control circuit comprising a source of alternating current; an output circuit; a contact element forming a switch, said switch being in series with said source and said output circuit; a rectifier in parallel with said switch; a commutating reactor having a main coil in series with said switch and said source of alternating current, and a reactor core; a transformer, said transformer having a continuous transformer core and a secondary winding; said main coil being wound common to the reactor core and said continuous transformer core; said main coil acting as a primary winding for said transformer; said secondary winding of said transformer being in series with said rectifier; means responsive to the energization of said rectifier, said commutating reactor and said transformer for opening said switch; said means having a regulated coil in series with said rectifier and said secondary winding; said regulator coil being energized prior to the opening and prior to the closing operation of said switch; said switch having two magnetic poles and an armature; said magnetic poles electrically insulated from each other; said magnetic poles forming stationary contacts to be engaged by said armature; biasing means to normally bias said armature away from said magnetic poles.

17. An electromagnetic control circuit comprising a source of alternating current; an output circuit; a contact element forming a switch, said switch being in series

with said source and said output circuit; a rectifier in parallel with said switch; a commutating reactor having a main coil in series with said switch and said source of alternating current, and a reactor core; a transformer, said transformer having a transformer core and a secondary coil; said main coil being wound on said reactor core and said transformer core acting as a primary for said transformer; a first winding for said switch; said secondary coil of said transformer being in series with said rectifier and said first winding; and said first winding responsive to the energization of said rectifier and said commutating reactor and said transformer for operating said switch; said secondary coil of said transformer being short circuited by a second secondary winding of a second transformer; said second transformer providing pre-excitation current for said secondary winding of said transformer through said second secondary winding; a regulation circuit for controlling the voltage to said output circuit; said regulation circuit comprising a continuous saturable core, a regulation coil, a main coil and a control coil; said main coil connected in series with said commutating reactor, the main coil and said source of alternating current; said regulator coil connected in series with said rectifier and said secondary coil; said control coil energized by a direct current source; the magnitude of said direct current source controlling the magnitude of output voltage at said output circuit.

18. An electromagnetic control circuit for a magnetic rectifier comprising a continuous saturable reactor core and a continuous transformer core; a main coil wound common to said continuous commutating reactor core and said continuous transformer core; a biasing coil wound on said continuous saturable reactor core; said biasing coil controlling the change in saturation of said saturable reactor core; a secondary winding wound on said continuous transformer core; said secondary winding being short circuited by a reactor; said reactor supplying a pre-excitation current to said secondary winding; said electromagnetic control circuit effective to maintain the current of said magnetic rectifier at substantially zero during the period that the contacts of said magnetic rectifier are closing and opening; said switch of said magnetic rectifier comprising stationary contacts and a movable armature cooperating therewith; said stationary contacts being formed from magnetic poles electrically insulated from each other; one of said poles having a coil wound thereon and connected in series with said secondary winding; the other of said magnetic poles having a coil wound thereon connected in series with said main coil.

19. An electromagnetic control circuit for a magnetic rectifier comprising a continuous saturable reactor core and a continuous transformer core; a main coil wound common to said continuous commutating reactor core and said continuous transformer core; a biasing coil wound on said continuous saturable reactor core; said biasing coil controlling the change in saturation of said saturable reactor core; a secondary winding wound on said continuous transformer core; said secondary winding being short circuited by a reactor; said reactor supplying a pre-excitation current to said secondary winding; said electromagnetic control circuit effective to maintain the current of said magnetic rectifier at substantially zero during the period that the contacts of said magnetic rectifier are closing and opening; said switch of said magnetic rectifier comprising stationary contacts and a movable armature cooperating therewith; said stationary contacts being formed from magnetic poles electrically insulated from each other; one of said poles having a coil wound thereon and connected in series with said secondary winding; the other of said magnetic poles having a coil wound thereon connected in series with said main coil; said first mentioned coil of said magnetic pole energized prior to the engagement of said movable armature with said stationary contacts; said second mentioned coil on said other magnetic pole energized after the engagement of said movable armature with said stationary contacts.

5 20. An electromagnetic control circuit comprising a rectifier and a regulator coil in series; a source of alternating current; a contact element forming a switch; an output circuit; said switch being in series with said source and said output circuit; said rectifier and regulator coil being 10 connected in parallel with said switch; first means operable by energization of said control circuit closing said contact element; and second means in series with said switch energized upon the closing of said contact for maintaining said contact closed; said switch comprising 15 magnetic poles and a movable armature; said magnetic poles electrically insulated from each other; said movable armature biased away from said magnetic poles; said moving armature and said magnetic poles forming cooperating contacts; said first means comprising a coil wound on 20 one of said magnetic poles and in series with said rectifier and said regulator coil; said second means comprising a coil wound on the other of said magnetic poles connected in series with a main winding of a saturable reactor.

25 21. A self-controlled rectifier comprising a source of alternating current, an output circuit, an electromagnetic switch, a combined commutating reactor and an electromagnetic regulator; said electromagnetic switch comprising magnetic poles and a movable armature which is spring 30 biased away from said magnetic poles; a main winding wound on one of said magnetic poles and a control winding wound on the other of said magnetic poles; said combined commutating reactor having a continuous reactor core, a continuous transformer core, a main coil wound 35 common to said continuous reactor core and said continuous transformer core; a secondary winding wound on said continuous transformer core; means to limit the residual current through said main coil after closing and before opening of said switch to a small value; said electromagnetic regulator comprising a continuous reactor core having a regulator coil, a control coil and a main coil wound thereon; said regulator coil connected in series with said secondary winding; said main coil of said electromagnetic 40 regulator connected in series with said main winding of said combined commutating reactor; said control winding of said electromagnetic regulator having direct current energization; said control coil determining the time of saturation of said regulator core; said regulator coil limiting the current through said main winding of said magnetic pole to a value insufficient to operate said electromagnetic switch when said regulator core is unsaturated; said main coil of said combined commutating reactor 45 limiting the rise of current through said control winding of said magnetic pole until said continuous reactor core saturates.

50 22. A control circuit for a magnetic rectifier to control the operation of a pair of cooperating contacts comprising a regulator coil, an electromagnet directly controlling the opening and closing of said cooperating contacts; said electromagnet having a main winding and a control winding; said control winding being connected in series with a dry cell rectifier; said control winding effecting the closing of said cooperating contacts when current flows 55 through said dry cell rectifier; said main winding being connected in series with said cooperating contacts and energized by the closing of said contacts to maintain said contacts closed; said control winding connected in series with and energized through said regulator coil; said regulator coil wound on a continuous core; a main winding 60 wound on said continuous core; said main winding of said regulator connected in series with said main winding of said electromagnet; a direct current energized pre-excitation winding wound on said continuous core of said regulator; said regulator main winding, said pre-excitation 65

70

75

winding, said regulator coil and said dry cell rectifier forming a magnetic amplifier.

23. In a self-controlled rectifying circuit comprising a pair of cooperating contacts and a dry cell rectifier; an electromagnet controlling the opening and closing of said cooperating contacts; a main winding and a control winding for said electromagnet; a regulator circuit comprising a continuous saturable core having a main winding, a pre-excitation winding and a regulator winding; said control winding of said electromagnet connected in series with said regulator winding and said dry cell rectifier; said main winding of said electromagnet connected in series with said main winding of said regulator; said pre-excitation winding of said regulator being energized by a direct voltage; said control winding effecting the closing of said cooperating contacts when current flows through said dry cell rectifier and said regulator winding when said continuous regulator coil is saturated; said main winding of said electromagnet being connected in series with said cooperating contacts and energized by the closing of the cooperating contacts through said main winding of said regulator to maintain said cooperating contacts closed; said main winding of said regulator limiting the value of current through said main winding of said electromagnet until said cooperating contacts are in full engagement; said regulator circuit and said dry cell rectifier forming a magnetic amplifier for said magnetic amplifier; said cooperating contacts moved to disengagement by biasing means.

24. In a magnetic amplifier comprising a combined commutating reactor, a regulating reactor, and an electromagnetic switch means for converting energy from an alternating current source to direct current and direct voltage to an output circuit; said combined commutating reactor comprising a continuous reactor core and a continuous transformer core; a main winding wound common to said continuous reactor core and said continuous transformer core; a pre-excitation winding for said reactor core; a secondary winding for said continuous transformer core; said regulator circuit comprising a main coil, a pre-excitation coil and a regulator coil; said electromagnetic switch means comprising a first and second magnetic core electrically insulated from each other and a movable armature; said first magnetic core having a main winding thereon; said second magnetic core having a control winding thereon; a dry cell rectifier; said secondary winding being connected in series to a loop circuit comprising the regulator coil, the control coil of said electromagnetic switch, the dry cell rectifier, the first and second magnetic poles, the movable armature, the main winding of said regulator, and the main winding of said combined commutating reactor; said secondary winding causing current to flow through said loop circuit when said continuous transformer core is desaturated to thereby oppose the residual current which flows through said magnetic poles and said movable armature due to said main windings of said combined commutating reactor and said regulator.

25. In a magnetic amplifier for converting the energy from an alternating current source to direct current and direct voltage to an output circuit comprising a combined commutating reactor, a thermionic tube, and an electromagnetic switch device; said thermionic tube comprising an anode, a grid and a cathode; said combined commutating reactor comprising a continuous reactor core and a continuous transformer core; a main winding common to said continuous reactor core and to said continuous transformer core; a secondary winding wound on said continuous transformer core; said electromagnetic switch device comprising a first and second magnetic pole having a main winding and a control winding, respectively, wound thereon; a movable armature for said elec-

tromagnetic switch device; said secondary winding connected to the loop circuit comprising said control winding and said main winding of said electromagnetic switch, said main winding of said combined commutating reactor, said thermionic tube, said magnetic poles and said movable armature; a D. C. control circuit connected to said grid of said thermionic tube; said thermionic tube firing to permit current flow from said alternating current source through said secondary winding through said control winding of said magnetic switch through said thermionic tube to said output circuit when said movable armature is not in engagement with said magnetic poles; said thermionic tube connected in parallel with said movable armature and said magnetic poles; said thermionic tube firing before said movable armature disengages said cooperating contacts to thereby cause a reverse current through said magnetic poles and said movable armature.

26. In a magnetic rectifier comprising an electromagnetic switch having a main and a control winding; a commutating reactor having a main and pre-excitation winding; said main winding of said commutating reactor being connected in series with said main winding of said electromagnetic switch; a rectifier being connected in series with said control winding of said electromagnetic switch; means for controlling the magnitude of voltage through said control winding prior to the closing of said switch; said rectifier and said control winding shunting said main winding of said commutating reactor and said main winding of said electromagnetic switch; said pre-excitation winding of said commutating reactor causing said main winding of said electromagnetic switch to be energized after the energization of said control winding of said electromagnetic switch and the closing of said electromagnetic switch.

30 27. In a magnetic rectifier comprising an electromagnetic switch having a main and a control winding; a commutating reactor having a main and pre-excitation winding; said main winding of said commutating reactor being connected in series with said main winding of said electromagnetic switch; a rectifier being connected in series with said control winding of said electromagnetic switch; means for controlling the magnitude of voltage through said control winding prior to the closing of said switch; said rectifier and said control winding shunting said main winding of said commutating reactor and said main winding of said electromagnetic switch; said pre-excitation winding of said commutating reactor causing said main winding of said electromagnetic switch to be energized after the energization of said control winding of said electromagnetic switch and the closing of said electromagnetic switch; and means for controlling the flow of current through a series circuit comprised of said main winding and said control winding of said electromagnetic switch while said electromagnetic switch is closed; said last mentioned means including a transformer.
